UNITED STATES PATENT OFFICE

2,538,538

PRESSURE GASOLINE SPORTSMAN'S STOVE

Edward H. Stempel, York, Pa., and Sophus Rasmussen, Albert Lea, Minn., assignors to American Gas Machine Company, Albert Lea, Minn., a corporation of Minnesota

Application August 4, 1945, Serial No. 608,928

1 Claim. (Cl. 126—38)

1

This invention relates to compact, readily portable, pressure stoves for burning gasoline and other hydrocarbon liquids which are particularly adapted for use by sportsmen, campers, tourists and the like.

It is an object of our invention to provide a simplified, highly efficient and very compact sportsman's stove of the class described wherein the entire device, when carried, may be embodied in the form of a substantially cylindrical package with the working parts thereof encased and protected and of such size and weight that it may be conveniently supported from a belt, pocket or other parts of the wearing apparel of the user.

Another object is the provision of a sportsman's stove of the class described, comprising a combination pressure tank and base with an upstanding burner supported therefrom and with a collapsible cooking utensil support associated with the burner in combination with a dual purpose cap member which acts as a protective sheathing for the burner and its related parts and which further, serves the function of providing a cooking receptacle when our stove is operated.

Another object is the provision of an efficient, compact sportsman's stove which may be readily started out of doors and wherein the flame produced will not be materially affected by wind, although no special shielding means are provided.

Still another object is the provision in a stove of the class described, of efficient but materially simplified regulating valve structure for controlling the mixture fed to the burner and utilizing certain of the stove parts, including the conduit which connects the fuel tank with the burner, as a part of the valve mechanism.

Another object is the provision of a very small compact pressure gasoline stove which when compacted, for portability, has its burner and other parts encased, but which nevertheless, may be very quickly set up, started and utilized for cooking purposes.

These and other objects and advantages of our invention will be more apparent from the following description made in connection with the accompanying drawings, wherein like reference characters refer to the same parts throughout the several views and in which:

Fig. 1 is a front elevation, showing an embodiment of our invention in operation;

Fig. 2 is a top plan view with the combination closure cap and cooking receptacle removed;

2

Fig. 3 is a side elevation of the device in compacted form, with the closure cap attached;

Fig. 4 is a rear elevation of the same;

Fig. 5 is a top plan view of the same;

Fig. 6 is an enlarged, vertical section taken axially through the sportsman's stove in condition for operation; and

Fig. 7 is a detail cross section, taken on the line 7—7 of Fig. 6, showing the extensible handle for adjusting the regulating valve.

In the form of our invention illustrated, a pressure tank or fount 10 is provided, of cylindrical shape and having, as shown, a convex bottom 10a which is provided with an axially disposed, internally threaded filling sleeve 10b in which a detachable closure plug 11, is threadedly seated with sealing effect. The lower edge of tank 10 is preferably reinforced by connection with the annular marginal edge of the bottom 10a, to form an annular skirt 10c, acting as the base or pedestal for the entire stove.

A housing or fitting, designated as an entirety by the letter F, is axially mounted in the top of pressure tank 10, as shown, having a somewhat diminished, upstanding nipple 12a which is externally threaded and extended through a suitable, circular aperture in the top of the tank. An internally threaded clamping collar 13 engages the nipple 12a and clamps fitting F to the tank. Fitting F is provided with an axial passage of preferably circular cross section extending from its upper end (nipple 12a) to a point adjacent the lower end thereof. In the form shown, the lower end of this axial passage forms a small communication chamber 12b between the discharge end of a depending fuel pipe 14 which is connected at its upper and horizontally extending extremity 14a with a suitable lateral port 15 formed in fitting F. A vertical, 30 restricting and cleaner-carrying rod 16 extends axially of fitting F and as shown, is affixed to the lower end thereof by threaded connection 16a with a suitable threaded socket tapped therein. Concentrically surrounding the upstanding rod 16 and disposed in slight, spaced relation thereto, is a conduit 17, defining in conjunction with the rod 16, an upwardly extending annular fuel passage and this conduit or sleeve 17, adjacent its lower end, is externally threaded to 35 engage and interfit the threaded lower portion of the interior of fitting F, above the lowermost communication chamber 12b. A frusto-conical valve seat 12d of small dimensions, is provided in fitting F just above the communication chamber 12b, disposed concentrically of the axial pas-

40

45

50

55

sage for cooperation with the lower extremity 17a of the upstanding conduit, to form a regulating valve. The edge of the end 17a of the conduit is beveled to snugly fit the frusto-conical seat 12d when the valve is closed.

A suitable packing gland G is applied between the top of nipple 12a of the fitting and the intermediate portion of conduit 17, as shown; comprising a packing nut having interposed therein and extending internally of nipple 12a and externally and in packing relation to conduit 17, a plurality of collars or annular washers 18, 18a and 18b respectively, the medial one of which as shown, is constructed of compressible, liquid-impermeable material.

To the upper end of conduit 17, a torque-receiving nipple 19 is rigidly affixed, said nipple having a hexagonal, channelled base portion 19a which is surrounded by the loop of a metal strap 20, provided with co-axial apertures in the outer and opposing ends thereof, for receiving an extensible handle rod 21 which also fits the channel of element 19a for securing the handle and strap 20 in operative position for applying torque to the conduit 17. The handle 21 is provided with a non-conductive finger-piece 21a at its outer end and is also provided with stop collars 21b and 21c located respectively at the opposite end and at an intermediate portion thereof, for limiting the extended and retracted position of the handle relative to strap 20.

The burner and entire super structure is supported by nipple 19. To this end, a sleeve fitting 22 has threaded engagement at 22a with the upper portion of nipple 19 and is enlarged at its upper portion to provide a wick-receiving well 22b for holding suitable wick material 23 about and surrounding the medial portion of the generator tube 24. Sleeve fitting 22 carries at its upper end, a spider basket comprising a plurality of radially extending, horizontal arms 25 which have rigidly attached to the outer ends thereof, upstanding arm pivoting sleeve 25a wherein the depending shanks 26a of inverted L-shape, utensil supporting arms 26 are pivotally and slidably disposed. An upstanding, arm anchoring finger 27 is provided for each of the supporting arms 26, preferably constructed of resilient material and having their upper ends 27a preferably bent inwardly and with the extremities or upper edges notched at 27b to provide seats appropriately related to the arms 26 to anchor the same, as shown in Figs. 2 and 6 in outward, radially extending position to furnish a grill for support of a frying pan or other cooking utensil.

The generator tube 24, as shown, is provided with an outwardly flared, lower extremity having a truncated conical, terminal flange for tightly seating against the extremity of nipple 19. Generator tube 24 is clamped to the nipple as shown, by an overhanging, annular flange, internally provided on sleeve fitting 22 which engages the upper edge of the flared, lower end of generator tube 24. Generator tube 24 is constructed of suitable metal having good heat conductive qualities, such as bronze or copper and as shown, has mounted therein, a spirally disposed wire or small spring 24a, to restrict surging or flash-backs during combustion of the burner. The upper end of generator tube 24, is internally threaded to receive and support the externally threaded lower end of a burner tip 28, provided with the usual axial orifice 28a. An internally threaded sleeve 29 is threadedly secured to the upper end of generator tube 24 and is disposed concentrically in

spaced relation, as shown, to burner tip 28 and has affixed to the upper end thereof, an open top, upwardly flaring, burner shell 30, which is provided in its peripheral wall and adjacent the bottom thereof, with a plurality of relatively large air intake passages 30a. A flame spreader plate 31 of slightly concavo-convex shape is mounted at the top of shell 30 by suitable means such as radially projecting arms 31a which have down-turned extremities for engagement with the upper edge of shell 30. Flame spreader 31 is made of a suitable metal or other material which will withstand high temperatures. A vertical, shielding ring 32 is supported on the outer ends of spider arms 25 and may be slipped into operative position between the resilient fingers 27 and the several upstanding arm pivoting sleeves 25a. Burner shell 30 is provided with a bottom drain port 30b to supply fuel for starting to wick 23, below.

The orifice 28a of the burner tip is provided with a fine, axially disposed cleaning needle 16 secured to the upper end of the rigid, vertical, restricting rod 16.

Our improved construction includes a dual purpose cylindrical cap or shell 33 of approximately the diameter of pressure tank 10 and having a height sufficient, when inverted, to accommodate the entire superstructure of our stove. Thus, when the supporting arms 26 are slightly lifted, from their anchoring fingers and inturned in close relationship to the burner shell 30, cap member 33 may be applied as shown in Figs. 3 and 4, to enclose and protect the entire burner structure, supporting basket, handle 21 (retracted to the dotted line position shown) and parts connecting the tank with the burner. Cap member 33 is provided with a dual purpose anchoring means in the form of a U-shaped strap 34, pivoted on a pin 35 which passes through the ends of strap member 34 and having slot and pin engagement with pin 35 for longitudinal adjustment. A clamping nut 35a threadedly engaging one end of pin 35, is adapted to clamp the member 34 to the supporting bracket 36 in various angular positions such as the attachment position shown in Fig. 4 and the horizontal handle position shown in Fig. 1. The looped, outer portion of U-shaped strap 34 is adapted to engage over a laterally projecting plug member 36a which extends from the medial height of pressure tank 10.

As shown, tank 10 is provided with a very efficient type of pressure pump indicated as an entirety by the letter P. The pump as shown, comprises a horizontally disposed cylinder 37 having an apertured, externally screw threaded plug 37a in the outer end thereof for slidably guiding a plunger rod 38. Plunger rod 38 is provided, adjacent its inner end, with a coarse preferably rounded screw thread 38a, which is adapted to threadedly engage the several parts of the pump piston and to furthermore, engage an internally threaded seat provided by a horizontal fitting 39 which is secured to the inner end of pump cylinder 37. The fitting 39 is provided with an axial air port 39a terminating in an external nipple 39b which forms a valve seat for engaging a valve disc 40a, removably inserted in a suitable, shallow, cylindrical socket formed in the inner end of a piston member 40 which is slidably mounted in the laterally extending plug member 36a and which is urged inwardly into engagement with the valve seat 39b by a coil spring 41 interposed between the closed end of the plug and the outer end of piston 40.

The horizontal fitting 39 is further provided with a radial and inwardly extending air discharge port 39c which is in communication with an annular groove 39d formed in the medial portion of fitting 39.

The combination protective cap and cooking utensil 33 is preferably provided with a depending clip 33a of resilient material attached to the top thereof and extending compactly against the peripheral wall, by which our entire stove, when encased for carrying, may be attached to a belt, loop or article of clothing worn by the user.

Operation

From the foregoing description, it will be noted that the entire stove may be very compactly collapsed and encased, forming a substantially cylindrical package with all parts of the device protected.

Our improved structure enables a highly efficient stove to be constructed, having a height in its compact form, of less than 7½ inches and a diameter of approximately 3 inches.

In utilizing our stove, the clamping nut 35a is released, the retaining member swung out of engagement with the plug 36a and the cap then removed from the stove proper. In doing this, the combination retaining member and handle 34 may be swung to a position radial of the cap 33.

The utensil-supporting arms 26 may then be swung outwardly in positions radial to the burner and lifted slightly and anchored in the notches 27b of retaining fingers 27. The valve regulating handle 21 may then be extended and turned slightly, whereupon gasoline or other hydrocarbon fuel from tank 10, is forced by pressure, through the depending conduit 14, the lower end of which, it will be noted, is disposed adjacent the peripheral interior wall of the tank at its lower portion. The gasoline will be directed through the orifice 28a overflowing the annular dam about the burner and some thereof, will find its way downwardly through port 30b, along sleeve 29 and conduit 24, to the wick 23 at the top of fitting 22. When a small amount of fuel has so accumulated, handle 21 may be turned to again seat the valve 17a against annular seat 12d at the lower end of the conduit 17. The gasoline then may be ignited by a match and after burning for some time, will heat generator tube 24 sufficiently to boil the hydrocarbon fuel, whereafter the regulating valve may be opened by turning handle 21 and the mixture ignited at the orifice of the burner. The intensity of the flame may, of course, be controlled by regulation of handle 21 which applies torque to the valve-forming conduit 17.

A frying pan or other cooking utensil may be supported above the burner and the radial arms 25 and distribution of intense heat from the flame is effected throughout a large area of the supported utensil, through the medium of the flame spreader supported above the burner.

The combination cap member and receptacle 33 in inverted position, with the dual purpose handle radially disposed, may be utilized as the cooking receptacle and in this connection, the closed end of the cap member is preferably made to conform to the space between the inner ends of arms 25 to form a nice fit in its support above the burner.

Pump structure P is of course utilized to, from time to time, supply pressure within tank 10 and in this connection, the pump plunger is first released by unscrewing the same from its threaded

inner end engagement with the horizontal fitting 39. In disengaging the plunger from stationary fitting the rounded threads 38a are in engagement with the several parts of the pump piston and the piston may then be reciprocated to force air through the axial air port 39a, opening the disc valve 40a and discharging air under pressure into the tank. When the desired pressure is obtained, the plunger is again thrust to its extreme inward position and then turned clockwise to again lock the threads 38a with fitting 39. In doing this, it will be noted that the inner extremity of plunger rod 38 is of conical formation, tightly fitting an annular valve seat, afforded by the axial passage or air port 39a of the fitting whereby a positive closure valve in addition to the check or disc valve 40a, is provided for sealing the air in the tank. It will of course be understood that the aperture in plug 37a and through which rod 38 works is sufficiently large to permit the supply of air from atmosphere to the pump cylinder on the back stroke of the piston.

In lighting or starting our stove as well as in the normal operating combustion, the burner as well as starting wick 23, is shielded from wind by the simple expedient of the removable vertical shielding ring 32.

The said shielding ring 32 may be readily removed for cleaning and the interior of the burner shell may be readily cleaned by removing the flame spreader 31 from the upper edge of the shell.

From the foregoing description, it will be seen that we have provided an exceedingly compact sportsman's stove comprising a minimum number of parts associated and combined to have, in many instances, dual functions and providing for a complete encasing and protection of all working parts in a compact form for carrying or attachment to the apparel of the user.

It will of course, be understood that various changes may be made in the form, details, arrangement and proportions of the parts without departing from the scope of my invention.

What is claimed is:

A sportsman's stove having in combination a base, a burner structure supported on said base and projecting thereabove, radial outwardly projecting members carried by said burner structure in spaced relation below the upper portion thereof, upstanding sleeves carried by the outer ends of said members, L-shaped utensil supports having horizontal and vertical arms, the vertical arms being pivotally mounted in said sleeves for swinging movement of the horizontal arms into inwardly swung relation over said burner structure and for outwardly swung relation projecting radially outwardly from said burner structure, and retainers for anchoring said horizontal arms in outwardly swung relation, said retainers being of spring construction and being secured to said radial outwardly projecting members and having upwardly and inwardly inclined notched end portions, the vertical arms of said supports having limited vertical movement in said sleeves to permit the horizontal arms of the supports to be readily carried over the notched end portions of said retainers as the horizontal arms are outwardly swung.

EDWARD H. STEMPLE.
SOPHUS RASMUSSEN.
